UNITED STATES PATENT OFFICE.

FRANCIS M. HAZLETON, OF SIERRAVILLE, CALIFORNIA.

STACKING LUMBER.

SPECIFICATION forming part of Letters Patent No. 719,663, dated February 3, 1903.

Application filed September 26, 1902. Serial No. 124,935. (No model.)

To all whom it may concern:

Be it known that I, FRANCIS M. HAZLETON, a citizen of the United States, residing at Sierra-ville, county of Sierra, State of California, 5 have invented an Improvement in Stacking Lumber; and I hereby declare the following to be a full, clear, and exact description of the same.

My invention relates to improvements in 10 stacking lumber, and is especially designed for the care of the "stickers," so called, which separate the lumber, and the protecting roof-boards.

It consists of a series of posts set between 15 each of the lumber-stacks and having trans-verse bars or sections attached at intervals between the top and bottom for the purpose of holding the stickers. These posts also have caps at the top which receive joists 20 across the two ends of the stack, and these joists serve to carry a roof or covering to pro-tect the lumber from sun and weather. The object of this is to provide a means for pre-serving the roof-boards and stickers and hold- 25 ing the latter in place for convenient use.

In the accompanying drawing the figure illustrates my invention.

A represents a stack of lumber built up with stickers 2 inserted between the layers, 30 so as to separate them to admit air for dry-ing and seasoning.

When lumber-stacks are taken down, the stickers are usually thrown upon the ground or upon trucks and considerable time is lost 35 in bringing them to the point where they are needed when a stack is to be again built, be-sides breakage and damage, and roof-boards, which are usually laid upon the stack, must also be thrown down in the same way.

40 3 represents posts which are set in the ground intermediate between each two adja- cent stacks, and these posts have cross bars or arms 4, fixed to them and projecting a lit-tle way on each side toward the stacks. These 45 arms or bars serve to receive the stickers when the lumber-pile is being taken down, so that the stickers are supported at about the level where they will be needed, and they

are always convenient whenever a new stack is to be built. The upper ends of the posts 50 are provided with caps 6, which are adapted to receive joists 7, extending across the two ends above the lumber-stack for the purpose of carrying a roof or covering. The posts are high enough so that this roof or covering is 55 above the highest point to which the stack will be built, and it may remain permanently in place when the stack is taken down or re-built. In this manner the roofing-boards, not being disturbed, will last a long time. The 60 stickers, being removed as the stack is taken down and laid upon the cross bars or arms, are always convenient and at hand for use when the stack is being rebuilt, and the series of cross-bars allow stickers to be supported 65 at every level where they will be needed.

The saving in the cost of handling lumber by this method is about ten per cent.

Having thus described my invention, what I claim, and desire to secure by Letters Pat- 70 ent, is—

1. A lumber-stacking device including cor-ner-posts having horizontal projections at dif-ferent elevations upon which the stickers are placed, cross-timbers connecting the upper 75 ends of the posts, and a roof or covering sup-ported upon the cross-timbers said roof and corner-posts forming an inclosure for the stack of lumber.

2. In a lumber-stacking device the combi-nation of vertical posts extending the height 80 of the stack and provided with caps, joists ex-tending across from one cap to another, and a roof or covering supported upon the joists said roof and posts forming an inclo-85 sure for the stack and said posts having hori-zontal projections at different elevations upon which the stickers are placed when removed from the stack.

In witness whereof I have hereunto set my 90 hand.

FRANCIS M. HAZLETON.
